UNITED STATES PATENT OFFICE.

WILLIAM C. BARDENHEUER, OF BROOKLYN, NEW YORK, ASSIGNOR TO BOORUM & PEASE COMPANY, OF NEW YORK, N. Y., A CORPORATION OF NEW YORK.

BOOK.

1,370,265.

Specification of Letters Patent.

Patented Mar. 1, 1921.

Application filed April 22, 1920. Serial No. 375,789.

To all whom it may concern:

Be it known that I, WILLIAM C. BARDENHEUER, a citizen of the United States of America, residing at 696 East 19th street, 5 borough of Brooklyn, city of New York, and State of New York, have invented certain new and useful Improvements in Books, of which the following is a specification.

My invention relates to books, and particularly to books of the loose-leaf binder type. The object of my invention is to improve the construction at the back of the book in the several features hereinafter described or shown in the accompanying drawings, in which—

Figure 1 is a perspective view of a loose-leaf book or binder in which my invention is embodied in one form;

Fig. 2 is an exploded view showing portion of the cover and parts in elevation;

Fig. 3 is a section on the line 3—3, Fig. 2;

Fig. 4 is a vertical section on the line 4—4, Fig. 2, showing the parts assembled;

Fig. 5 is a perspective of the end cap;

Fig. 6 is an elevation of a back plate of modified construction;

Fig. 7 is a perspective of another modified form of the back plate;

Fig. 8 is a partial elevation of a back plate of the type shown in Fig. 7, partially assembled with the cover;

Figs. 9 and 10 are sections on the lines 9—9 and 10—10, Fig. 8, respectively;

Fig. 11 is a partial elevation showing a further modified construction partially assembled with the cover; and

Fig. 12 is a perspective of a back plate and end cap rigidly united by welding, or soldering.

In the construction shown in Figs. 1 to 5 inclusive, the book or binder comprises a cover 15 of flexible material, such as leather. To the interior of the cover back is secured a lining strip 16 of fabric or thin leather, 5 which may be either glued in place, or stitched, as at 17, Fig. 3, or both glued and stitched, as in the construction shown. A concaved metal back plate 18 with inwardly curved marginal flanges 19 is not only glued 45 to the lining piece 16, but securely held in

position by the overlapped side flaps 20 of the latter, which are glued and smoothed against the inside of the marginal channels and inner face of the back plate. In order to neatly finish the lining at the ends of the 55 back plate the side flaps 20 are slit at 21 and folded inward before gluing in position.

It will be noted that the end of the back plate is thus left exposed (as shown at the top of Fig. 2), and that the cover 15 is held 60 against the outer face thereof only by the lining piece 16. Moreover, upon the assembly of the ring carrier 22 by springing it within the flanges 19 of the back plate and pushing it longitudinally in the usual manner to latch the tongues 23 of the back plate in the holes 24 in the inner wall of the ring carrier, the flaps 21 of the lining piece are 65 very apt to be torn away from the back plate and forced beyond the end of the carrier. When this occurs the end flaps become conspicuous, and being loose soon fray out and become unsightly. Moreover, the cover 15 may become loose at the ends of the 70 back plate as the glue dries or cracks and this further detracts from the appearance, as well as the wear, of the back. Again, when the cover projects beyond the end of the back plate, the edge of the latter is apt to cut through the cover, especially after 75 the latter has worked somewhat loose from the back plate.

These objectionable features of construction have now been remedied by providing a thin metal end cap concaved to the curvature of the back plate and comprising an inner flange 25 adapted to fit within the back plate and overlie the flaps 21 (Fig. 2), and an outer flange 26 slightly spaced from the back plate to accommodate the edge of the 80 cover 15 which it overlies (Fig. 1). The cap may be held in place by any suitable means, such as by staking the inner flange at 27 to the back plate. The cap thus serves not only to hold the lining flaps 21 against 85 displacement during the assembly of the ring carrier 22, but also to hold the ends of the cover back snugly against the plate 18. At the same time the cap affords a durable 90 wearing surface at the opposite ends of the 95 100

back, and thus protects the cover from wear or injury at this point, which is one of the most vulnerable in the construction of the binder.

5 In Fig. 6, a modification is illustrated in which the end cap, instead of forming an independent piece, is integral with the back plate. Thus, at the upper end of Fig. 6 the back plate is shown with an extension 28, 10 which in finished condition, shown at the lower end of the figure, is recurved over and spaced slightly from the outer face of the back plate to receive the edge of the cover 15. When this construction is used the 15 cover is slipped beneath the previously recurved flange 28, which may be then further compressed against the cover to hold it firmly as well as protect it against wear.

In Fig. 7 I have shown a back plate 29 20 from which the recurved side margins 19 are omitted. In this construction the ring carrier 22 is held in assembled position by the tongues 23, which pass through the holes 24 in the inner face of the ring carrier. 25 Low studs 30 formed in the ends of the back plate take into holes 31 in the inner face of the ring carrier and prevent longitudinal displacement of the parts after assembly. The back plate 29 has sufficient spring not 30 only to permit the slight deflection necessary when engaging the tongues 23 in the holes 24, but also to enter the studs 30 in the holes 31 after the engagement with the tongues 23 has been effected. Obviously the 35 studs may be formed on the inner portion of the ring carrier and entered into the holes in the back plates 29 if preferred.

It will be noted that in this construction 40 the lining pieces 16^a overlie the side margins of the back plate and are carried outward therefrom to the side boards 32 here used to stiffen the cover, as is usual with a fabric cover. The side board facing 33 overlaps this lining piece 16^a and thus aids in holding it 45 in position. The side boards 32 are spaced slightly from the back plate, so that the cover and lining piece 16^a form a hinge at 34, for the sides of the book cover. The end cap or flange 28 is extremely valuable 50 in a construction of this sort to strengthen and support the fabric cover 35 at the end of the hinge areas 34.

In Fig. 11 the lining piece 36, instead of 55 passing beneath the back plate 18 is secured at its outer margin to the side board 32 of the cover and is carried over the side flanges 19 of the back plate and glued to the inner faces thereof, thus affording a reinforcing hinge construction of the type shown in 60 Figs. 7 to 10, but applied to a flanged back plate type of construction. In this figure the end cap is also shown as an independent member, which is fitted in position after the other elements are assembled.

65 In Fig. 12 the end cap is shown welded,

soldered, or otherwise permanently secured at 37 to the back plate 18. This affords a construction substantially like that of Fig. 6, but may be used where it is found more convenient to shape and finish the end cap 70 independently of the back plate.

Various other modification will readily occur to those dealing with the problem, which do not depart from what I claim as my invention. While I have shown the 75 inner flange 25 of the end cap longer than the outer flange 26, the particular relation of the flanges may be varied. I have found it an advantage, however, to make the inner flange 25 longer since it facilitates the assembly of the parts, by reason of the fact that the ring carrier rests upon the flange at the moment the tongues 23 enter the holes 24 in the ring carrier, so that upon the shoving home of the ring carrier there is no 85 danger that the end of the plate will be engaged by the carrier and the cap thus displaced, or the assembly impeded.

In the following claims I use the words "end cap" in a sense broad enough, where 90 the context permits, to include a flange integral with the back plate as shown in Figs. 6 to 10 inclusive, and the claims are to be read on this understanding.

I claim—

1. In a loose-leaf binder, a cover, a metallic back plate, means for securing the same within the back of the cover, and an end cap permanently associated with said back plate and embracing the edge of the 100 cover at the back of the binder to protect the same and to hold it firmly against the back plate.

2. In a loose-leaf binder, a cover, a concaved back plate, means for securing the 105 same within the back of the cover, and an end cap permanently associated with said back plate and shaped to the contour, but spaced from the outer face thereof, said end cap embracing the edge of the cover at the 110 back of the binder to protect the same and hold it firmly against the outer face of the back plate.

3. In a loose-leaf binder, a metallic back plate having tongues projecting inwardly 115 therefrom, a loose-leaf ring carrier having its inner face apertured to receive said tongues on the back plate, said back plate having rigid stud means, and the ring carrier having co-operating recess means to hold the ring carrier against longitudinal displacement on the back plate after the tongues on the latter have been engaged through said apertures in the ring carrier, together with a binder cover within the back 120 of which said metallic back plate lies, and an end cap on the back plate embracing the edge of the cover at the back of the book and serving to hold the same against the back plate.

4. In a loose-leaf binder, a cover, a metallic back plate arranged within the back of the cover, a flexible lining engaging the cover and back plate to reinforce the hinge
5 area adjacent the back plate, and an end cap associated with the back plate and embracing the edge of the cover at the back of the

binder to strengthen the hinge, protect the cover and hold the latter firmly against the back plate.

In testimony whereof I have signed my name to this specification.

WILLIAM C. BARDENHEUER.
